GOLF CLUB CARRIER

John L. Findeisen, 11026 S. Ave. L,
Chicago, Ill. 60617

Filed Oct. 12, 1973, Ser. No. 405,917

Term of patent 14 years

Int. Cl. D21—02

U.S. Cl. D34—5 GB

FIG.1

FIG.5

FIG.6

FIG.2

FIG.3

FIG.4

FIG. 1 is a perspective of a golf club carrier embodying my new design.

FIG. 2 is a side elevation of the golf club carrier of FIG. 1.

FIG. 3 and FIG. 4 are face and back elevations, respectively of the golf club carrier shown in FIG. 1 and FIG. 2.

FIG. 5 and FIG. 6 are top and bottom views, respectively of the golf club carrier shown in FIG. 1 and FIG. 2.

I claim:

The ornamental design for a golf club carrier, as shown.
